(57) **CLAIM**

The ornamental design for the charger for medical transmitter, as shown and as described.

DESCRIPTION

FIG. 1 is a bottom, rear, left side perspective view of a charger for medical transmitter, showing our new design.

FIG. 2 is a front elevation view thereof.

FIG. 3 is a rear elevation view thereof.

FIG. 4 is a top plan view thereof.

FIG. 5 is a bottom plan view thereof.

FIG. 6 is a left side elevation view thereof.

FIG. 7 is a right side elevation view thereof; and,

FIG. 8 is a bottom, front, right side perspective view of the charger for medical transmitter of FIG. 1, shown in a condition for use.

The broken lines in the drawings depict portions of the charger for medical transmitter that form no part of the claimed design. In FIG. 8, the broken lines showing a transmitter depict environmental subject matter only and form no part of the claimed design.

1 Claim, 8 Drawing Sheets
